IGNITION TIMING MEANS

Kenneth A. Harmon, Longmeadow, Mass., assignor to Wico Electric Company, West Springfield, Mass., a corporation of Massachusetts

Application April 10, 1936, Serial No. 73,773

4 Claims. (CL 123—117)

This invention relates to improvements in ignition timing means for internal combustion engines. The invention is particularly useful in connection with automobile engines which need to be sufficiently flexible in operation to adapt themselves to wide variations in speed and load.

The conventional form of ignition timing control for automobile engines now generally used utilizes a centrifugal governor and a vacuum taken from the intake manifold at a location adjacent the throttle valve. The centrifugal governor advances and retards the time of ignition in direct proportion to engine speed, within the limits of its range of action. Beyond a certain speed, the centrifugal elements are arrested by a stop which limits their action but up to this point the spark is advanced substantially in direct proportion to engine speed. The vacuum is utilized conjointly with the governor for varying the timing of ignition. The vacuum is caused to advance or retard the spark according to increase or decrease in the suction prevailing in the intake passage. The vacuum control, by itself, provides variations in timing in accordance with variations in the density of the charge taken into the engine cylinders. As the amount of the charge of fuel mixture taken into a cylinder increases by a wider opening of the throttle valve, the compression of the charge in the cylinder increases and thus the density of the charge increases. As is well known, the rate of flame propagation through the fuel mixture increases with its density,—other factors being equal. Thus, as the charges of larger volume are taken into the cylinder, the ignition spark should occur later to offset the increased rate of flame propagation in the denser charge. However, the vacuum control does not operate alone. It acts jointly with the centrifugal governor and the two do not combine in the right way to secure the desired result. The effect of the governor is always present, except at the extreme high speeds, and it counteracts the retardation secured by the vacuum. The spark advance, referred to, is for level road operation at various constant speeds. The vacuum control alone would more nearly satisfy the conditions although it would not fully do so. The governor control is needed to provide the spark advance for varying loads under a wide open throttle condition. But it acts at all times and disadvantageously affects the vacuum control under constant speed conditions for level road operation.

This invention has for an object to provide a control for the ignition timing which is largely

independent of engine speed; which enables the elimination of centrifugally-operated spark control devices with the many troubles and disadvantages incident thereto; and which depends entirely on the engine-produced suction existing in the intake passage of the engine,—utilizing the suction produced at two different points in said passage to secure a timing control which has much better characteristics than those obtainable with the conventional control described.

More particularly, it is an object of the invention to provide a timing control actuated jointly by two vacuum-operated means, one of which responds to the vacuum existing in the intake passage of the engine at a point adjacent the throttle valve and the other of which responds to the vacuum existing in said passage at or near the venturi or the point at which fuel is supplied to said passage.

The two vacuum-operated means combine and by their joint action produce a spark timing curve for constant speed, level road operation with the desired characteristics, particularly with reference to gradual retardation of the spark with increasing speeds to compensate for mixtures of increasing density and the resulting increasing rate of flame propagation. The vacuum at the venturi does not, like the governor, adversely affect the action of the vacuum at the throttle. It does not, like the governor, act at the same rate at all times. Rather, it acts beneficially at times, when needed, to supplement the vacuum at the throttle and enable characteristics of spark timing to be secured by joint action which could not be secured by the independent action of either or secured by the conventional control described. The Venturi vacuum which functions as a measuring means for the fuel supplied to the engine, and is utilized here for the additional purpose of spark control and it provides a timing curve for wide open throttle conditions, which is considered superior to that effected by the usual centrifugal governor. It advances the spark in direct proportion to the fuel supplied as measured by the vacuum at the venturi. The spark advance is not directly proportional to engine speed as it is with the centrifugal governor. But aside from this advantage which is important, it is of great importance to be able to dispense with a centrifugal governor which has been a source of many troubles to the trade.

These and other features of invention will best appear as the detailed description proceeds and they will be particularly pointed out in the appended claims.

The invention will be disclosed with reference to the accompanying drawings, in which:

Fig. 1 is a diagrammatical view showing an ignition timing apparatus embodying the invention; and

Fig. 2 is a chart illustrative of the operation of the apparatus shown in Fig. 1 and of the spark-timing characteristics secured by use of such apparatus.

10 Referring to Fig. 1 of these drawings; 5 represents the intake passage in the pipe 6 through which the mixture of fuel and air is drawn into the engine cylinders to be ignited. Air is admitted to passage 5 at the end 7 and fuel is supplied thereto at another point, as by the pipe 8 which leads from the fuel supply chamber 9 of the carburetor. In the intake passage 5 and located beyond the point at which fuel is admitted and in position to control the amount of the mixture 20 of fuel and air supplied to the engine cylinders, is the usual throttle valve 10. A venturi 11 is provided in passage 5 between the throttle valve and the air admission opening, and the fuel is usually drawn in as shown, at the throat or location of greatest constriction of the venturi.

These parts have been illustrated simply in conventional form because they are the usual adjuncts of an internal combustion engine and their use and purposes are well understood.

30 The timer, likewise, has been shown simply in conventional form since its construction and operation is well understood in the art. The timer includes a pair of contacts 12 and 13, the former being carried by an arm 14, pivoted at 15 to a member 16 and movable in radially inward direction by a spring 17. The contact 13 is fixed to member 16. One of the contacts is insulated from member 16 in any suitable manner. The contacts 12 and 13, which are moved into engagement by spring 17, are separated by a cam 18 mounted on a shaft 19 forming a part of or driven from the internal combustion engine. This cam engages a rubbing block 20, fixed on the breaker arm 14. The member 16 is mounted for angular 40 adjustment relatively to cam 18 and its shaft 19. By moving member 16 clockwise the time of ignition will be advanced and by moving it counterclockwise the time of ignition will be retarded.

For actuating the timer, I utilize the suction 50 developed at two spaced locations in the intake passage 5, one adjacent the throttle valve and one adjacent the point of fuel admission. The best locations, I believe, are those shown, wherein the opening 21 is so located as to be closed by the throttle valve when that valve is closed and wherein the opening 22 is located at the throat of the venturi. The suction produced at 21 is added to that produced at 22 and the two effects, combined, are utilized through the intermediary 55 of any suitable means to actuate the timer, advancing it as the total suction increases and retarding it as the total suction decreases.

An exemplary form of such an intermediary means is shown in Fig. 1. Here two bellows are 60 mounted one within another on a suitably fixed support 23. The inner bellows 24 is connected by a pipe 25 to the opening 21 while the outer bellows 26 is connected by a pipe 27 to the opening 22. Both bellows act on the same member 70 28 and this movable member carries a rod 29 which is suitably connected, as by the pin and slot connection shown, to an arm 30 on the breaker plate 16. The spring of the bellows may serve as the force working in opposition to the engine- 75 produced suction to move the breaker plate in

a counterclockwise direction or a separate spring such as shown conventionally at 31 may be used for this purpose.

It is to be understood that the apparatus shown in Fig. 1 is merely an exemplary form. It is an 5 illustrative example of one of many forms which may be used to carry out the invention and the invention is not to be limited to the one specific form disclosed. Any means which will respond to the vacuum existing in the intake passage at the locations described, and effect timing adjustments of the circuit breaker may be used, as desired. The two means need not necessarily act together on the breaker plate, as shown. All that is necessary is to produce an angular movement between the cam and breaker lever and it is immaterial, insofar as this invention is concerned, which of these elements is shifted and, of course, it is equally feasible as is well known in the art to shift one element by one means and the other 10 element by the other means.

The operation of the invention will be explained with reference to the diagram of Fig. 2. In this figure the curves drawn in full lines represent 15 spark advance and are to be read with reference to the left hand scale of ordinates (degrees of spark advance at the engine). The curves drawn in broken lines represent vacuum and are to be 20 read with reference to the right hand scale of ordinates (vacuum in inches of water). The abscissae, the same for all curves, represent speed, 25 in this case translated into miles per hour of the automobile driven by the engine. The curve A shows the various degrees of vacuum which will 30 exist at the throttle opening 21 when the throttle is set to maintain various constant speeds on a level road. The curve B shows the various degrees of vacuum which will exist at the Venturi opening 22 for various speeds under the same condition. The curves C and D represent the vacuum 35 which exists at the throttle opening 21 and the Venturi opening 22, respectively, under a wide open throttle condition. Curve E represents the 40 spark advance produced as the result of the vacuum shown at C plus that shown at D. Curve F 45 represents the spark advance which would be produced if the vacuum represented at A were utilized alone, while curve G shows the actual spark advance which is effected as the direct result of the vacuum shown at A plus that shown at B. 50

The bellows 24 and 26 are of different cross sectional areas so that for the same degree of vacuum the larger bellows 26 will produce a larger degree of spark advance than the smaller. As herein shown, their areas are in the ratio of $4\frac{1}{3}$ 55 to 1. 30 inches of vacuum at the venturi will produce a spark advance of 20 degrees while 260 inches of vacuum will produce a spark advance of 40 degrees. The curve F is, of course, directly proportional to curve A. Curve G, however, is 60 proportional to the sum of curve F and the spark advance produced by curve B. If the spark advance secured for various speeds by the vacuum plotted at B be added to curve A, the result 65 will be curve G. For example, at a speed of 60 miles per hour, there is about 12 inches of vacuum at the venturi under the condition shown by curve B. This degree of vacuum will produce eight degrees of spark advance and curve G at the 60 mile per hour point will be found spaced 70 vertically eight degrees above curve F at the 60 mile per hour point. In combining curve C and D to get the spark advance curve E for wide open throttle conditions, the influence of curve C is practically negligible. For example, at a speed 75

of 60 miles per hour, the vacuum shown by curve C is about 15 inches but the spark advance resulting from this degree of vacuum is only about two degrees, while the 30 inch vacuum shown for the same speed by curve D produces a twenty degree spark advance.

The spark advance provided for level road operation, as shown by curve G, is much better adapted to the needs of present day, high compression, automobile engines than that produced by any of the prior art methods of which I am aware. From speeds of from 25 miles per hour upward, it provides the gradual retard in time of ignition necessary. Over the usual driving range, 15 say from 25 to 50 miles per hour, the retardation is at a substantially uniform rate. As the speed of the engine increases, the charges taken into the cylinders become greater and greater and thus the mixture taken into the cylinders is subjected 20 to more and more compression and becomes more and more dense. The rate of flame propagation in the mixture increases with the speed and later timing of the ignition is required to offset these increases. The curve A gives just this result. 25 From 55 miles per hour upward the rate of increase of compression is not as great due to the difficulty in getting full charges into the cylinders at the extreme high speeds and the spark advance curve G is designed to take care of 30 this condition by a less rapid rate of retardation. This change,—this flattening out of curve G beyond the 50 mile per hour point,—is due to the influence of the vacuum at the venturi. As shown by curve B, the influence of the vacuum at the 35 venturi is practically negligible up to a speed of 45 miles per hour. It starts out almost horizontal and nearly coincident with the horizontal base line of the diagram and does not diverge to any great extent from such line until a speed of 30 miles per hour is reached and then only to a slight degree. But beyond the 45 mile per hour point it begins to curve upwardly at a greatly increased rate and produces an increasing degree of spark advance at a time when the vacuum 40 at the throttle opening is causing a too rapid retardation of the spark. The effect of the vacuum at the venturi at high speeds is to offset to some extent the effect of the vacuum at the throttle and give the result desired as shown by the 45 curve G. The curve B, it will be seen, is not directly proportional to speed. The speed effect is evident only at the higher speeds in contradistinction to the usual arrangement where vacuum at the throttle plus centrifugal control is 50 used. In such case, the centrifugal control provides a spark advance curve which is a straight line from zero to the point where the governor weights reach the limit of their movement when the curve becomes a horizontal line (at the extreme high speeds). Thus, the centrifugal governor modifies a vacuum curve, such as A, by adding to it uniform increments at all points from zero to the high speed at which it ceases to function, and thereafter at the extreme high 55 speeds it has no additional effect. In this case the curve A is not substantially modified until a speed of about 25 miles per hour is reached and the greatest modification occurs when the extreme high speeds are reached, at which time the 60 modification is needed. The governor therefore acts constantly up to a certain point and its effect is to give an advance in spark at the higher speeds where actually retardation is needed. The centrifugal governor working in conjunction 65 with a vacuum at the throttle cannot yield a re-

sult such as is shown by that part of curve G which lies in the speed range between the 25 mile per hour point and the extreme high speed limit.

The curve G, from zero to 25 miles per hour gives a rapidly increasing spark advance. At 5 idling speeds, a large retard is effected due to the closing off of the throttle opening 21 by the closing of the throttle. The most important and novel effects are found in that part of curve G beyond the 25 mile per hour point. 10

The spark advance curve E for wide-open throttle conditions provides for an advance which increases as the speed increases. It differs, however, from the advance obtained with a centrifugal governor, the curve for which is a straight line of uniform slope from zero up to the limit of its action. Curve E is essentially made up of two straight line portions,—the initial portion (up to 25 miles per hour) having a much more gradual slope than the remaining portion. The result 20 is a relatively small rate of spark advance for the engine when working at low speeds under heavy loads, and a more rapid rate of spark advance for the higher speeds and lighter loads. This spark advance, as will be seen from a comparison 25 of curves D and E is directly proportional to the vacuum at the venturi and not to speed. The amount of vacuum at the venturi determines the amount of fuel supplied to the engine and thus the spark advance for varying load conditions 30 under a wide open throttle is made in direct proportion to the amount of fuel supplied, which is considered a logical solution of the problem and a better one than to vary the spark in direct proportion to speed as is usually done with the 35 centrifugal governor.

The utilization of vacuum at the venturi as the means for securing the spark advance for wide open throttle conditions enables me to dispense entirely with the centrifugal governor, 40 which has quite generally been used for this purpose. The centrifugal governor, when used for ignition control of present day automobile engines, which have very high compression, presents many difficulties which were not experienced in the past. The modern engine is much more sensitive to timing. In many cases, a spark advance as low as 10 degrees is used and slight variations in the action of the governor, which variations would not be noticeable with the large 50 spark advances such as 30 to 45 degrees, formerly used, will materially affect the engine performance. Any looseness or play in the governor is taken up at the circuit breaker and causes variations in timing. For example, referring to Fig. 1, when the cam 18 engages member 20 to move the breaker arm outwardly, there is a tendency for the cam to be held back until any lost motion in the governor is taken up, with the result that there will be a slight retarding of the timing by 60 delay in opening the breaker points. Subsequently as the breaker arm moves inwardly, there will be a tendency for the cam to move rapidly ahead and cause a premature closing of the points. These tendencies will result in a pulsating action 65 of the circuit breaker if lost motion is present,—the governor not being able to hold the cam within close limits in its intended position with reference to the shaft. Space limitations preclude an increase in size of the governor to an 70 extent such as to definitely stop this trouble, whereas with the arrangement disclosed, the bellows may be made large enough to supply a large enough force to hold the adjustable element of the timer against such pulsating movements. The 75

modern engine, with its greatly increased range of speed, cannot be adequately served by the governor. If its weights are so made as to give the necessary power to start at low speeds, they move outwardly too fast at high speeds and are difficult to control. If they are made properly for the higher speeds, they fail to start at the lower speeds and, at best, all that can be obtained is a rough approximation of the results needed. 5 These governors are susceptible to wear and the wear results in play and causes variations in timing. With the Venturi vacuum utilized as disclosed, the mechanical troubles heretofore experienced with the governor, its tendency to pulsating 10 action and variations in timing are eliminated and a much better spark advance for wide open throttle conditions is obtained and one which is not likely to get out of order and which is not susceptible to rapid wear with resulting inaccuracies in timing. 15

It will be understood that the figures, referred to herein for speed, vacuum and spark advance, have been given by way of illustrative example and that they are not intended to be used as setting up limitations. The chart of Fig. 2 shows the 20 results of one typical case where the invention has been applied to a well known make of automobile. In this case, it was arbitrarily decided that a spark advance of 40 degrees was desired 25 at a speed of 25 miles per hour for the condition of constant speed operation on level road and that a spark advance of 20 degrees was desired at a speed of 60 miles per hour under the condition of a wide open throttle. The vacuum pressure 30 prevailing at these speeds, under these conditions, was made by the mechanism disclosed to effect the amount of spark advance named. Obviously, other figures for speed and spark advance could have been chosen as starting points. Also, the 35 range of speeds, the amount of vacuum and the degrees of spark advance may vary within wide limits. However, the one specific example given 40 is a typical one and fully illustrates the performance obtained by the use of the invention 45 when applied to automobile engines of the present day type.

The invention thus provides an improved ignition timing means, characterized in that the vacuum at two points in the engine intake is 50 utilized to secure by joint action a spark advance for constant speed, level road conditions having characteristics adapted for the modern automobile engine and in that a better spark advance is secured for wide-open throttle conditions by the 55 utilization of the vacuum at one or both of these points, than can be secured with the centrifugal governor.

What I claim is:

1. An ignition timing control for internal combustion engines, wherein air and fuel are admitted into an intake passage at spaced points and the mixture of air and fuel is drawn into the engine cylinders under reduced pressure to be ig- 60

nited and wherein said passage is provided with a throttle valve to control the amount of the mixture drawn into said cylinders, comprising, a circuit breaker, a cam for operating the breaker, and means for effecting a relative angular adjustment between the cam and breaker, said means responsive to the combined effect of the engine-produced suction in said passage at spaced points therein, one adjacent said throttle valve in position to be closed by the throttle valve when closed and one adjacent the point of admission of fuel. 5

2. An ignition timing control for internal combustion engines, wherein air and fuel are admitted into an intake passage at spaced points and the mixture of air and fuel is drawn into the 15 engine cylinders under reduced pressure to be ignited and wherein said passage is provided with a throttle valve to control the amount of the mixture drawn into said cylinders and with a venturi at the location where fuel is admitted, 20 comprising, a circuit breaker, a cam for operating the breaker, and means for effecting a relative angular adjustment between the cam and breaker, said means responsive to the combined effect of the engine-produced suction in said passage at 25 spaced points therein, one adjacent said throttle valve in position to be closed by the throttle valve when closed and one at the throat of said venturi. 30

3. In an internal combustion engine, having an intake passage provided with a venturi and a throttle valve, ignition timing means, a device actuated by fluid pressure and having a conduit connection with said intake passage opening into the latter at a point such that said connection will be closed by the closing of the throttle valve, a device actuated by fluid pressure and having a conduit connection with said intake passage opening into the latter at the throat of said venturi, and means connecting said devices to said timing 35 effects of both devices. 40

4. In an internal combustion engine, having an intake passage provided with an air admission opening, a throttle valve and a venturi located between said valve and opening, an ignition timing means, and operating means for the timing means comprising a device subjected to and movable responsive to a suction in said passage at a point adjacent said throttle valve and having a conduit 45 connection with said intake passage opening into the latter at a point such that said connection will be closed by the closing of the throttle valve, a device subjected to and movable responsive to the suction in said passage at the throat of said 50 venturi, and connections between said devices and timing means for summing up the movements of said devices and operating the timing means proportionately to the sum of such movements, advancing the timing means as total suction 55 increases and retarding it as the total suction decreases. 60

KENNETH A. HARMON.
